(57) **CLAIM**

The ornamental design for a jewelry hanger, as shown and described.

DESCRIPTION

FIG. 1 is a perspective view of a first embodiment of a jewelry hanger showing my new design;

FIG. 2 is a front elevational view of the first embodiment thereof;

FIG. 3 is a rear elevational view of the first embodiment thereof;

FIG. 4 is a left side elevational view of the first embodiment thereof;

FIG. 5 is a right side elevational view of the first embodiment thereof;

FIG. 6 is a top plan view of the first embodiment thereof;

FIG. 7 is a bottom plan view of the first embodiment thereof;

and,

FIG. 8 is a perspective view of the first embodiment showing the jewelry hanger use.

The portions shown in broken lines are included for illustrative purposes only and form no part of the claimed design.
